SEAL FOR OVERLAPPING METAL BANDS

Ian Waveney Girvan, Shilla, Denham, England
Application February 9, 1938, Serial No 189,634

In Great Britain November 3, 1937

5 Claims. (Cl. 24—20)

This invention relates to an improved seal for overlapping metal bands, such as are used for strapping boxes, cases and the like.

One object of the present invention is to provide a band seal of the type described which includes a tension lock, as well as a face lock.

Another object is to produce a band seal which does not involve the provision of upstanding free-ended tongues.

Still another object of the invention is to provide a band seal in which the band is not weakened by any transverse cuts.

According to the invention, these and other objects which will appear more clearly as the specification proceeds, are accomplished by the arrangements set forth in the following detailed description, defined in the appended claims, and illustratively exemplified in the accompanying drawings, in which:

20 Figure 1 is a plan view of the overlapped parts of the metal band strap, showing one embodiment of the present invention.

Figure 2 is a side elevation of the overlapped parts of the band according to Fig. 1, before the 25 sealing movement.

Figure 3 is a plan view of the overlapped parts of the band according to Fig. 1 after the same have been mutually displaced to produce the seal.

Figure 4 is a plan view of the overlapped parts 30 of a modified form of the invention.

Figure 5 is a side elevation of the band according to Fig. 4, before the sealing movement.

Figure 6 is an enlarged plan view of the parts 35 of the band in the embodiment of Fig. 4 showing the same in the position which they assume when they have been mutually displaced to produce the seal.

Figure 7 is a plan view of the overlapped parts of a further modification.

40 Figure 8 is a plan view of the overlapped parts of the band showing a still further modification of the invention.

Figure 9 is a side elevation of the band according to Fig. 8, before the sealing movement has 45 occurred.

Figure 10 is a plan view, on a larger scale, of the form shown in Figure 8, illustrating the relative position of the parts after relative movement between the overlapped parts of the band has 50 taken place.

Figure 11 is a plan view of the overlapped ends of the band showing a further form of the present invention.

55 Figure 12 is a side elevation of this form of the invention showing the parts of the ends of the

band before the sealing movement has taken place.

Figure 13 is plan view showing the completed seal provided by this form of the present invention, and

Figure 14 is a section on line 14—14 of Figure 13 illustrating the "face-lock" effect which is secured by means of this arrangement.

It must be clearly understood that the present invention is not limited to any particular construction or form of sealing machine. The slits may be cut and the tension on the band released (or relative movement of the overlapped parts of the band caused in any other way) by means of any suitable construction of machine whether it 10 be operated by one or two levers.

Referring first to Figures 1 to 3 of the accompanying drawings, 10 and 11 represent respectively the upper and lower parts of the overlapped ends of a metal band strap encircling a 20 packing case or other article to be strapped (not shown). The band, in effecting the seal, is first placed under tension to any desired degree by means of a strapping machine of any suitable construction. The encircling metal band having 25 been placed under the required tension, there is cut therein by means of suitable dies in the strapping machine a plurality of pairs of individually independent slits. Any desired number of pairs of identical slits may be cut without departing 30 from the scope of the present invention but it is believed that three such pairs of slits will be quite sufficient to give an efficient and effective seal for all normal purposes.

Each pair of slits is identical and so only a 35 single pair and the operation of the same will be described. Each pair of slits comprises a part 12 inclined at an acute angle to the marginal border of the band strap, the slits converging towards one another to a point of closest approach 13 40 after which they are continued parallel to one another or, as shown in the drawings, diverging from one another as at 14. The actual shape or mutual relation of the continued part 14 of the slits is immaterial in carrying out the present invention. They may, as above stated, even be parallel with one another, all that is necessary is that this continuation of the slits shall be such that it facilitates the relative movement of the overlapped parts 10 and 11 of the band, as hereinafter described.

That part 15 of the overlapped parts of the band between the slits 12 and 14 is displaced, preferably though not essentially at the same time as the slits are cut, downwardly from the 55

plane of the overlapped parts of the band in such a manner that, at the point 13 of closest approach of the mutually converging slits 12 the upper surface of the upper band 10 is moved below the under surface of the under band 11, whilst at the point 16 of widest separation of the slits 12 the under band is not displaced. The continuation or extension 14 of the slits 12 facilitates this special displacement as will be readily appreciated from Figure 2.

It may be pointed out here that instead of the part 15 of the ends 10 and 11 of the band being displaced downwardly, they may equally well be displaced upwardly without departing from the scope of the present invention. Two advantages are, however, secured by displacing this part of the ends of the band downwardly. In the first place, there will be no projections whatsoever from the upper surface of the upper band 10 and, in the second place, since there will be a tendency for the band to bind on to the tapering dies, it will be easier to free the same when the upper male die moves.

If it be assumed that the dies which are adapted to cut the slits 12 and their extensions 14 are also adapted to displace the band between the slits then, after the slits have been cut, the relative positions of the overlapped parts of the band is that shown in plan in Figure 1 and in side elevation in Figure 2. It should be particularly noted that the method of sealing according to the present invention does not necessarily involve the vertical displacement of the margins 16 of the overlapped parts of the band.

After the slits have been cut and the parts of the overlapped ends of the band depressed as described above, the tension on the band is released, for example, by severing the encircling band from the stock coil, whereupon relative movement of the two parts of the band takes place in the direction of the arrows shown in Figure 2. The parts thereupon take up the position shown in Figure 3.

Since that part of the upper band 10 between the mutually converging slits 12 has been pressed down completely through the corresponding part of the under band 11 (see Figure 2), it will be appreciated that when relative movement between the upper end of the band and the lower end of the band takes place in the direction of the arrows shown in Figure 2, the converging edges of the part 15 of the upper band 10 between the slits 12 will engage with and even bite into the corresponding edges of the slits in the margins 17 of the under band 11 to give a transverse bite or seal, the effective value of which increases proportionally to the amount of movement which takes place between the upper and lower parts 10 and 11 of the band. Any effort to separate the overlapping parts of the band still further in this direction will, therefore, tend to increase the transverse bite or seal between the overlapping parts of the band. It is for this reason that I refer to the main locking or sealing action of the arrangement according to the present invention as a "tension-lock."

It follows that since the part 15 of the upper band moves relative to the corresponding part of the under band the edges will, to a certain extent, overlap as shown in the shaded portions 18 of Figure 3. At these parts 18 there is a portion of the upper band underlying and overlapping the under band thus giving a "face-lock" which will prevent the easy separation of the overlapped parts of the band in a vertical direc-

tion. With the construction shown in Figures 1 to 3 this "face-lock" is comparatively small and it is for this reason that certain of the constructions hereinafter described are to be preferred.

It will be appreciated that the efficacy of the tension lock according to the present invention will to a large extent depend upon the angle of convergence of the slits 12, but in considering this point due account must be taken of the possibility of separating the overlapping parts 10 and 11 of the band vertically, i. e., the desirability of providing an adequate "face-lock." Whilst, therefore, it is obvious that the greater the angle of convergence between the slits 12 the greater will be the "tension-lock" secured, it must be remembered that by just so much as the angle of convergence is increased, so, with the arrangement illustrated in Figures 1 to 3, will the effective "face-lock" against vertical displacement be decreased. This is due to the decreased effective overlap of the displaced parts, as will be readily understood. This overlap is shown by means of the shaded parts 18 in Figure 3 and the same will obviously be controlled by the extent of the movement which takes place when the tension is released. This in turn is obviously controlled by the angle of convergence of the slits 12. For this reason I have found it to be of benefit to limit the angle of convergence to the slits 12 to form 5 to 15°.

The less the angle of convergence between the slits 12 the greater will be the edge surface entering into the mutual engagement to give what I have referred to above as the "tension lock", i. e., a lock which increases as the tension of the overlapping parts of the band increases in the direction of the arrow shown in Figure 2. But, as above stated, due account must be taken of the "face-lock" or ability to prevent vertical separation of the overlapped parts of the sealed band. Therefore, the angle of convergence should not be too small. I have found that with the construction illustrated in Figures 1 to 3 an angle of convergence of from 6° to 10° is satisfactory.

Obviously it is not necessary that the slits 12 in the construction illustrated in Figures 1 to 3, or in any of the constructions described herein-after, need be straight; they may be curved to any comparatively large radius or may be of any other suitable shape as desired.

A more effective "face-lock" may, however, be secured by means of the modification of the shape of the slits as shown in Figures 4 to 6 of the accompanying drawings. In this construction the same slits 12 mutually converging are provided as in the construction shown in Figures 1 to 3, but instead of immediately communicating with the diverging slits 14 the same are inclined more sharply as at 20 then round as at 21 to diverging slits 22 and are finally continued as parallel slits 23, these parallel slits serving to facilitate the relative movement of the overlapped parts of the band.

The construction illustrated in Figures 4 to 6 has also the advantage that it will facilitate the manufacture of the dies necessary to cut the slits and to displace the parts of the band between the slits. Otherwise the tension-lock secured is the same assuming the included angle between the converging slits 12 is the same. The "face-lock" effective to prevent separation of the overlapped parts of the band in a vertical direction is, however, increased as is obvious from the shaded parts 24 of Figure 6 which indicate the

effective overlap of the under and upper band which prevent separation of the overlapping parts of the band independent of the "tension-lock" provided. The arrangement illustrated in Figures 4 to 6 differs from that illustrated in Figures 1 to 3 in so far as it provides an improved "face-lock" which tends to prevent unauthorised vertical separation of the overlapping parts 10 and 11 of the band, and like reference numerals 10 have been used to indicate like parts.

Figure 7 illustrates a slight modification of the shape of the slits shown in Figures 4 to 6. In this modification the mutually converging slits 12 are, as shown in Figures 4 to 6, continued as 15 more sharply converging and curved or straight parts 30 and then continue as diverging parts 40 which form, in effect, the chord to the part 22 and 23 shown in Figure 4. Otherwise the operation is the same.

20 Figures 8 to 10 illustrate a construction of strapping band-lock or seal which is, in effect, a duplicate of the seal illustrated in Figures 1 to 3.

In this arrangement the converging slits 12 of each pair of slits are merged into parallel portions 25 41 and are then continued for substantially the same distance as the parts 12 as a diverging pair of slits 42 (or what may be considered as an opposed pair of converging slits). The displacement of the metal between the converging 30 and diverging slits 12 and 42 respectively is then opposed (upwardly and downwardly for example) and a double transverse tension lock will be obtained, as will be readily appreciated. Furthermore, counter transverse bites (Figure 10) will 35 with such an arrangement be set up close to the apices of the obtuse angles 50 should it be attempted to release the seal by means of a reverse movement of the overlapped parts of the band.

Figures 11 to 14 illustrate a simple and very 40 strong form of seal according to the present invention. In this arrangement, elongated slots 60 are cut in the overlapped parts of the band, these slots being interrupted at a suitable point by semi-circular or other appropriately shaped 45 indentations 61. If desired, the indentations 61 may be formed as like projections extending into the margins of the band without departing from the scope of the present invention. It is also to be noted that, whilst it is convenient to continue 50 the slots on the narrower side (or right-hand side as shown in the drawings) of the indentations 61 as strict continuations of the slits 60 so that the slit as a whole is of yoke shape, the said continuations, which are designated by 62, correspond to the continuation slits 14 of Figures 1 55 to 3 and may accordingly be of any shape which will allow relative movement of the overlapped parts of the band without departing from the scope of the present invention.

60 The strip of the bands 10 and 11 defined by the slits 60, 61 and 62 is displaced downwards (or upwards as above explained) so that the part 61 of the one band passes completely through the corresponding aperture in the other band (see 65 Figure 12, which shows the position of the parts before the relative movement has taken place). The tension is thereupon released and relative movement takes place. As far as the "tension-lock" is concerned, the parts 60 of the slits (and 70 also the parts 62 if they form strict continuation of the slits 60) correspond exactly to the

slits 12 of the arrangement illustrated in Figures 1 to 3 and give an effective tension-lock as explained in connection with the said construction. It is, however, in connection with the face-lock secured that this arrangement is particularly advantageous. It will be seen, on reference to Figures 13 and 14 that the parts adjacent the following edge of the slit 61 in the upper band will become positioned under the marginal portions of the under band, as indicated by the shaded 10 parts 64 in Figure 13, to give a very effective face-lock.

Obviously the converging slits may be straight or curved as desired and as far as each pair is concerned may be directly opposed transversely 15 of the band or may be staggered along the length of the same as desired.

It will be readily appreciated that the main sealing is obtained by means of the transverse bite 20 between the two ends of the band and since the band at the material part is not weakened by any transverse slit or cut a much lower quality of steel and/or a narrower band may be used than with prior constructions including free-ended tongues produced by transverse cuts.

25 In all cases, it should be clearly understood that the slits of each pair are quite independent of and do not communicate with one another in the seal according to the present invention.

I claim:—
1. In a seal for overlapping metal bands, two superposed band portions provided with a pair of substantially longitudinal slits defining between them longitudinal strips integral at their ends with the respective bands, both said strips having midportions of reduced width bent out of the respective planes of their bands to leave therein aligned openings having correspondingly restricted midportions, the strip cut from one of said bands having its midportion bent through 40 the opening in the second band and offset beyond the plane of the same, and both strips tapering into said midportions, whereby upon displacement of said first band relative to the second band in the direction of the taper, the tapering edges 45 of the strip of the first band at their intersections with the tapering edges of the opening in said second band effect a tension lock while simultaneously a wider section of the offset midportion of the strip of the first band comes to 50 overlap the edges of the opening in the second band at said restricted midportion of said opening to provide a face lock.

2. A seal for overlapping bands, as claimed in claim 1, in which the tapering edges of said 55 strips converge towards one another at an angle between 5° and 15°.

3. A seal for overlapping bands, as claimed in claim 1, in which the tapering edges of said strips have outer portions converging towards 60 one another at a smaller angle and inner portions converging towards one another at a greater angle.

4. A seal for overlapping bands, as claimed in claim 1, in which each of said midportions comprises a section having parallel edges.

5. A seal for overlapping bands, as claimed in claim 1, in which each of said midportions comprises two longitudinally adjoining sections of substantially different widths.

IAN WAVENY GIRVAN.
